UNITED STATES PATENT OFFICE.

ADOLPH VON SCHLUEMBACH, OF ALTOONA, PENNSYLVANIA.

FOLDING BOX OR CRATE.

1,376,487.

Specification of Letters Patent.

Patented May 3, 1921.

Application filed April 18, 1919. Serial No. 291,071.

To all whom it may concern:

Be it known that I, ADOLPH VON SCHLUEMBACH, a citizen of the United States, residing at Altoona, county of Blair, 5 and State of Pennsylvania, have invented certain new and useful Improvements in Folding Boxes or Crates, of which the following is a specification.

My invention relates to folding boxes or 10 crates, and particularly to devices of this character wherein the sides and ends are hingedly connected to the top element and the sides and ends have a sliding connection with the bottom element.

15 The object of my invention is to provide an improved device of the class mentioned in which the edges of the top and bottom sections shall lie close together and flush when the crate is folded, and wherein the sides and 20 ends shall be perfectly vertical when the box is in expanded position. A further object of my invention is to provide a folding box or crate which shall be strong and durable to stand shipping when either in its expanded or collapsed position, and which 25 shall be of sufficient strength to securely hold substantially any material which can be packed within the same. A further object of my invention is to provide improved 30 means for slidably connecting the lower portion of the sides to the bottom. Other objects will appear hereinafter.

With these objects in view, my invention consists generally in the various combinations and arrangements of parts, and in the 35 details of construction, hereinafter described and particularly pointed out in the claims.

40 My invention will be more readily understood by reference to the accompanying drawings forming a part of this specification, and in which—

Figure 1 is a vertical longitudinal section of the folding crate embodying my invention.

45 Fig. 2 is a vertical transverse section of the same on substantially the line 2—2 of Fig. 1.

Fig. 3 is an end elevation of the device in 50 folded position.

Fig. 4 is a detail perspective view of one of the bottom elements to which the sides are slidably connected.

Fig. 5 is a side elevation, partly in section, 55 illustrating a modified form of the device.

Fig. 6 is a perspective view of one end of

the crate or box in expanded position and illustrating the metallic reinforcing elements.

Figs. 7 and 8 are detail perspective views 60 of elements used in modified forms of the device.

Fig. 9 is a perspective view of the bottom reinforcing elements.

Fig. 10 is a detail perspective view of the 65 interior upper corner of a modified form of box.

Fig. 11 is a perspective view similar to Fig. 4, illustrating a modified form of said element.

70 Fig. 12 is a section on the line 12—12 of Fig. 11 upon an enlarged scale.

Fig. 13 is a bottom plan view of the portion of the device illustrated in Fig. 12.

75 Figs. 14 and 15 are fragmentary perspective views of modified form of the said bottom element, and

Fig. 16 is a side elevation of a still further modification.

Referring now to the drawings, 1 and 2 80 indicate generally the top and bottom, respectively, of the folding box or crate embodying my invention, 3, 3 the ends, and 4, 4 the sides thereof. In regard to the sides and ends, these may be of any general construction desired according to the use to 85 which the device is to be put; that is, they may be slatted as illustrated in Figs. 1 and 2 for use as a chicken crate or the like, or may be solid walls as illustrated in Figs. 5, 90 6 and 10, when the device is to be used as a packing, shipping, or storage box. With this understanding, I shall hereinafter designate the device as a crate, it being understood that said terms shall include either solid or 95 slatted construction, except when the specific construction is mentioned or described as such.

The top 1 comprises a pair of parallel longitudinal members 5, 5, and a pair of transverse end members 6, 6. In the form of the device illustrated in Figs. 1 to 6 inclusive the side elements 5 are of less width vertically than the end member 6 and the sides 4 are hingedly connected to the members 5 so 100 that the outer faces of the sides and said members shall lie flush when the box is in expanded position, as shown clearly in Figs. 2 and 6. The hinge connection between the sides 4 and the members 5 may take the form 105 of ordinary hinges 7 as shown in Figs. 1 and 2, particularly when the open crate construc-

tion is used, or may constitute dowel pins 8 let into the members 6, as indicated in dotted lines in Fig. 5. The difference in the vertical widths of the members 5 and 6 is substantially equal, or slightly greater, than the thickness of the sides 4, so that when said sides fold inwardly the lower edges of the members 6 may rest upon the end frame members 9 of the bottom. Also, the portions 10 of the members 6 extending below the lower edges of the members 5 provide for bearings for the dowels 8 when such construction is employed. The end members 3 are hingedly connected to the top 1 by dowels 10 having 15 bearings in the side members 5 above the pivotal axis of the sides 4 so that said ends may swing upwardly against the top and then the sides fold against and under said ends. It will be noted that when the box is 20 in expanded position the ends 3 rest between the ends of the sides so as to hold the same locked in expanded position.

The bottom 2 comprises a pair of end members 9 connected by a bottom 11 and 25 also by the metallic reinforcing framework 12. The members 9 are provided with slots or runways 13 in which projections 14 on the lower ends of the sides are adapted to travel. These projections 30 are preferably pins provided with anti-friction rollers, and I also prefer to provide washers 15 on the outer ends thereof which travel in enlarged outer portions 16 of the runways 13. See Fig. 4. The projections 14 constitute means for connecting the bottom to the upper portion of the device. To fold the box, the ends 3 are raised into the position shown in dotted lines in Fig. 1, after which the lower portions of 40 the sides are forced inwardly, the members 14 traveling in the runways 13, until the top 1 rests upon the bottom 2, as shown in Fig. 3. To expand the box, the top is raised and the members 14 move outwardly 45 in the runways 13 until they reach the outer ends thereof, the ends 3 either dropping or being moved downwardly into vertical position, lock the sides and form a rigid construction. A closure 17 is provided which 50 is preferably rabbeted into the upper frame as shown clearly in Figs. 1, 2, 5 and 6. Any means may be employed for connecting the closure to the upper frame, such as hinges 18.

55 The reinforcing member 12 for the bottom of the device preferably comprises a pair of end channel members 19, 19, which embrace the outer and lower faces of the members 9, thereby closing the outer faces 60 of the runways 13 and longitudinal members 20 connecting the same. The vertical portions of the angle members 19 are extended the desired distance along the sides of the device and constitute stops to limit 65 the outward swing of the sides 4 in the

construction shown in Figs. 1 to 6 inclusive. Metal angle brackets 22 are provided to reinforce the corners of the top frame. These are shown clearly in Figs. 5 and 6.

If preferred, the vertical edges of the 70 sides members may be provided with metal reinforcing elements 23 or 24, as shown in Figs. 7 and 8, respectively, and these are provided with outwardly projecting pins 8' at their upper ends and 14' at their lower 75 ends, to constitute pivot dowels at their upper ends and sliding members at their lower ends to engage in the runways 13. As shown in Fig. 7, these elements may be of simple angle irons or they may be channel members as shown in Fig. 8, their use being dependent largely upon the size of the box and the use to which the same is to be put.

In Figs. 11 to 13 inclusive I have shown 85 a modified form of the end elements 9 of the bottom frame. As shown therein, said element is formed of a metal strip bent to form a horizontal bottom 9^a, vertical ends 9^b, horizontal upper members 9^c terminating at the center where they are bent downwardly as at 9^d. The lower ends of the portions 9^d terminate in semi-cylindrical portions 9^e which project through an aperture 9^f in the lower portion 9^a. The semi-cylindrical portions 9^e are complementary to each other and are threaded to receive a nut 9^g, the whole forming a rigid construction. This arrangement provides a pair of runways 13' for the members 14. 95

As shown in Fig. 14, the member 9 may be formed of a casting slotted as at 13^a and provided with a pair of horizontal flanges 25 to receive the ends of the floor 11 between them. A similar construction is 105 shown in Fig. 15 except that the same is formed of sheet metal bent to form an upright flange 26 slotted at 13^a and formed with the horizontal flanges 25.

A still further modification of the element 9 is shown in Fig. 16. In this form of the device said element is formed of upper and lower metal bars 27 spaced apart by ferrules 28 and connected by rivets 29 extending through said ferrules. 110

In Fig. 10 of the drawings, I have illustrated a modified form of the device wherein the elements 5 and 6 of the upper frame are substantially the same depth and the ends and sides 3 and 4 respectively, are 120 pivotally connected to the upper frame by the dowel pins 30 and 31.

I claim:

1. A folding box or crate comprising a top and a bottom co-extensive in length and 125 width, sides hingedly connected to said top and having a sliding connection with the bottom, and ends hingedly connected to the top and swinging downwardly between said sides, substantially as described. 130

2. In a folding box or crate, a top frame comprising side and end members, a bottom, sides hingedly connected to the top and adapted to lie directly beneath said side members of the top when the box is in expanded position with the outer faces of said members and sides in the same vertical plane, a sliding connection between the lower ends of said sides and said bottom, and ends hingedly connected to said top and adapted to swing downwardly between the said sides, substantially as described. 45
3. A folding box or crate comprising a top and a bottom co-extensive in length and width, sides hingedly connected to said top, said bottom having end members provided with slots, projections on the lower ends of said sides working in said slots, members closing the outer sides of said slots, and ends hingedly connected to the top and swinging downwardly between the said sides, substantially as described. 50
4. A folding box or crate comprising a top and a bottom co-extensive in length and width, sides hingedly connected to said top, said bottom having end portions provided with slots, projections on the lower ends of said sides working in said slots, bottom brace members, said brace members having flanges closing the outer sides of said slots and ends hingedly connected to said top and swinging downwardly between the said sides, substantially as described. 55
5. A device as set forth in claim 4 in which said flanges are extended along the sides of the bottom, substantially as described. 60
6. In a folding box or crate, a top comprising a frame formed of side and end members having their upper edges in the same plane, the lower edges of the end members extending below the lower edges of the side members of the frame, sides for the box hingedly mounted beneath the side members of the frame, a bottom, a sliding connection between the lower ends of said sides and said bottom, and ends adapted to swing between the said sides, substantially as described. 65
7. In a folding box or crate, a top and a bottom, a pair of sides, reinforcing elements on the vertical edges of said sides, hinge members on one end of said reinforcing elements, projections on the opposite ends of said elements, said bottom being provided with slots to receive said projections, and ends swingingly mounted between said sides, substantially as described. 70
8. A device as set forth in claim 3 in which the end members of the bottom are formed of metal strips slotted to receive the projections on the sides, substantially as described. 75
9. A device as set forth in claim 3 in which said slotted end members of the bottom are each formed of a metal strip extending horizontally substantially the width of the bottom, then bent upwardly and then inwardly to substantially the center, and then downwardly terminating in complementary semi-cylindrical portions, the bottom portion being apertured to receive said semi-cylindrical portions, and a nut threaded on said portions, substantially as described. 80
- In testimony whereof I have signed my name to this specification in the presence of two subscribing witnesses.
